UNITED STATES PATENT OFFICE

2,026,297

VISCOMETER

John Montgomery Bell, Chester, S. C.

Application April 21, 1934, Serial No. 721,791

8 Claims. (Cl. 265—11)

The object of this invention is to provide simple and reliable mechanism for indicating the viscosity of a liquid with a great degree of accuracy, this being accomplished by eliminating as much as is practicable the friction generated by the elements which are relied upon for measuring purposes, as more fully hereinafter set forth.

In the drawings annexed, Fig. 1 is an elevation of one side of the apparatus, some of the non-essential parts being broken away.

Fig. 2 is an elevation of another side of the apparatus, parts of the frame being in vertical section.

Fig. 3 is a vertical central sectional view of my apparatus.

Fig. 4 is a detail view in vertical section of the lower end of the shaft for suspending the viscosity-measuring-disc.

Fig. 5 is a plan view, the top motor and parts of the frame being broken away.

Fig. 6 is a horizontal sectional view on the line 6—6 of Fig. 3.

Fig. 7 is a detail horizontal sectional view showing more particularly the circuit controlling device associated with the measuring disc, the section being taken on the line just above the springs 36.

Fig. 8 is a diagram of the electrical control devices all of which, except a motor 59 may be for convenience and protection enclosed in a box 95 mounted on the top of the frame of the machine.

Fig. 9 is a vertical section in detail of the measuring-disc suspension means.

Figs. 10 and 11 are additional diagrams of the motor-control system.

Referring to the drawings annexed by reference characters, 10 designates a tank for holding the liquid whose viscosity is to be measured and indicated, this tank being provided with an inlet 11 and an overflow outlet at 12 and also a clean-out device at 13. Extending up through a stuffing box in the bottom of the tank is a shaft 14 which at its upper end is provided with a driven disc 15 arranged horizontally within the tank, at a point below the liquid level therein. This shaft is supported by a collar 16 and is held tight by a coil spring 17 arranged between the stuffing box and the hub of a drive wheel 18 on the shaft 14. This shaft 14 is driven at a pre-determined speed by any suitable mechanism, preferably by an electrical synchronous motor 19, the drive shaft of this motor being connected up to the wheel 18 by means of a set of worm gearing 20, a vertical shaft 21, a belt-wheel 22 and a belt 23.

The center of the disc 15 is provided with an inlet cup or well 24 into which the liquid in the tank enters through one or more perforations 25. Above this driven disc is suspended a viscosity-measuring-disc 26, the plane of this disc being parallel with the plane of the driven disc and its axis of rotation being concentric therewith. The two discs are preferably of the same diameter. The upper disc is affixed to the lower end of a tubular shaft 27 whose upper, flanged end is attached by screws 28 to a cross-bar 29 which extends through a transverse slot in a vertical non-rotatable rod 30. The screws 28 clamp in place a spacing ring 31 and a circuit making and breaking finger 32. Inside the tubular shaft 27 is another rod 33 whose upper end is conically tapered to a point to form an antifriction bearing in the underside of the aforesaid bar 29. The upper end of rod 33 is affixed to the lower end of rod 30 and the lower end of the rod 33 is stepped in an upstanding pin 34 supported by a tightly fitting plug 35 closing the lower end of the tubular shaft 27. In this way the upper, measuring-disc is suspended from the lower end of the rod 30 with the least possible frictional resistance to the oscillation of the measuring-disc and its connected parts, thereby rendering this measuring-disc extremely sensitive in its oscillations back and forth with reference to the driven disc 15.

It will be understood that while the constant-speed driving disc 15 is in rotation the liquid in the space between the two discs will tend to rotate the measuring-disc in the direction of rotation of the driven disc 15. The measuring-disc normally tends to oscillate or rotate in a direction opposite to that of the rotation of the driving-disc 15. In the present instance this normal tendency of the measuring-disc is obtained by a spring which consists of two coils 36 which have their inner ends connected by a wire or cord 37 and their outer ends hooked in holes in bars 38, these bars being affixed rigidly to a bar 39 extending through and fitting tightly in the upper part of the slot in the rod 30, at a point just above the aforescribed bar 29. The bar 39 is affixed rigidly to the underside of a plate 40, this plate 40 being provided with a hole midway its length for passage of the rod 30. Means for affixing the bar 39 to the plate 40 consists of two screws 41 threaded into the bar 39 and through arcuate slots 42, the purpose of the arcuate slots being to permit the spring 36—37 to be tensioned to thereby vary the degree of resistance to the driving tendency of the liquid confined between the discs. Adjacent one of the

55

arcuate slots is a scale 43, which, together with a pointer 44, assists in accurately setting the tension of the spring. In Fig. 7, the arrow within the receptacle shows the direction in which the spring tends to rotate the disc 26. By employing two coils 36 and an intermediate flexible wire 37 and arranging this wire 37 to bear upon opposite faces of a pair of spaced pins 45, the pull of the spring is so nicely balanced that practically all friction-engendering side-thrust on the bearing at the top of the shaft 33 is avoided.

It will be observed that the bar 39 moves only up and down with the rod 30 and that its connected parts including spring 36-37 and plate 40 move only with the bar 39; and to insure non-rotary action of the parts just referred to I provide a stop-pin 46 mounted on the frame and arranged to extend through a slot or hole in an arm 47 affixed to one end of the bar 39. The disc 26 and its connected parts also move up and down with the rod 30, and in addition this disc 26 is permitted, as stated, a slight oscillatory movement in both directions, the extent of this movement being determined by the two contact pins 48 insulatedly mounted on one end of the bar 39 and having connection through wires 49 with an electric motor hereinafter described. The finger 32 is provided at one end with an upstanding contact member 50 which makes electrical connection with the opposing ends of the contact pins 48.

From the foregoing it will be observed that while the apparatus is in use the spring tends to rotate the measuring-disc 26 in one direction while the liquid between the discs, being given a centrifugal action by the driving disc, tends to rotate by viscous drag action the measuring-disc in the opposite direction. When the drag of the liquid is sufficient to overcome the action of the spring the measuring-disc will be oscillated or rotated in the same direction as the driving disc and contact will be made between 50 and one of the contacts 48, whereupon the electric motor, hereinafter described, will be put into operation and through associated mechanism, hereinafter described, raise the rod 30 until the disc 26 is sufficiently elevated to reduce the drag so that it nicely balances the action of the spring, whereby the measuring disc will again come under the influence of the spring and be rotated in the opposite direction a distance far enough to at least break contact at 50-48, whereupon the motor will be cut out and upward movement of the measuring-disc will cease. The measuring-disc 26 and the circuit breaking finger 32 will remain in this nicely balanced position so long as the viscosity of the liquid remains the same. Should the viscosity of the liquid decrease, the spring will again come into action and oscillate or swing the disc in the opposite direction and thus bring the other contacts 50-48 into action and this will serve to reverse the action of the motor and thus lower the measuring-disc to a point where the changed viscosity will again be sufficient to move the measuring-disc against the action of its spring and thus nicely balance the parts in their changed position. In other words, thickening of the liquid brings about an elevation of the measuring-disc while a thinning down of the liquid brings about a lowering of the disc, since the thinner the liquid the nearer the discs must be to each other to cause sufficient drag on the measuring disc to keep its controlling circuit-breaking-and-making finger 32 in a balanced position, approximately midway between the two

contacts 48-48. It is important that the liquid be delivered to the space between the discs at the center thereof, and it is also important that at all times there shall be an ample supply of liquid to the space between the discs in order that the centrifugal action set up by the driving disc shall not tend to create a vacuum there-between, as that tendency would obviously destroy the accuracy of the apparatus. To keep a constant supply of liquid to the center space of the discs I not only provide the well 24 in the lower disc but I also dish upwardly the upper disc.

To prevent jiggling of the finger 32 I provide an oil dash-pot 51 which rigidly depends on the bar 39, in position to receive a flat blade 52 affixed to the end of the finger 32 opposite its contact 50. The rod 30 is moved up and down in a vertical bearing 53 by means of a screw 54 (formed by threading the upper end of the rod) and a nut 55 threaded on this screw and mounted within the hub of a worm-gear 56, which gear is driven by a worm 57. The worm 57 is affixed to a shaft 58 which is driven by an electric motor 59 through the medium of a belt 60, a pulley 61, a shaft 62, another belt 63 and another pulley 64 affixed to the shaft 58 carrying the worm. When the motor 59 is driven in one direction the screw 54 and nut 55 will cause the rod 30 to move upwardly whereas when driven in the other direction the rod 30 will be forced downwardly. The motor 59 is a reversible motor and is, as stated heretofore, rotated in one direction or the other according to which of the contacts 50-48 are in engagement. A scale is provided on the periphery of the worm-gear 56, which together with an associated pointer 65, indicates the position of the measuring-disc and therefore the viscosity of the liquid. If a further indication of the viscosity is needed I employ an additional indicating wheel 66 provided with a scale on its periphery associated with pointer 67, and I operate this additional indicating wheel by means of a pinion 68 affixed to its shaft and a rack 69 affixed to a rod 70, this rod being reciprocally supported in the frame and being resiliently pressed down on the upper end of the slideable rod 30. In this way the vertical movements of the rod 30 will be indicated on the scale on wheel 66.

In some cases it is desirable to utilize a scale on the worm gear for indicating fractions of units of measurement and a scale on the wheel 66 for indicating whole units. The structure obviously lends itself nicely to this division of the indicating means since even an entire revolution of the worm-gear scale 56 will raise or lower the rod 30 but a slight distance, only enough, for instance, to indicate one unit on the larger scale 66. Any suitable resilient means may be employed for holding the rod 70 down against the screw end 54; I illustrate two coil springs 71 surrounding vertical rods 72 and also another spring 73 coiled around the shaft of the scale wheel 66. It is desirable that the liquid in the tank 10 be kept stirred in order to avoid caking and I therefore provide two vertical stirrers 74 depending into the tank and provided with stirring blades 75, these stirrers being rotated by pulleys 76 attached to the upper ends of their shafts and driven by a belt 77, which in turn is driven by a pulley 78 affixed to a vertical shaft 79 which is power-driven by a belt 80 running over pulleys 81 and 82 affixed respectively to the aforesaid shaft 79 and the aforesaid shaft 21 of 75

the main motor 19. An idle pulley 83 is associated with the two pulleys 16 in order to drive the stirrers in opposite direction.

In Fig. 8 I show a preferred electrical arrangement for controlling the reversible motor 59 from the swinging contact member 32. The hereinbefore mentioned conductors 49 form the primary circuits of two transformers 84, and connected to this primary circuit 49 and the contact finger 32 are the respective terminals of the secondary circuit 85 of a spark coil 86 having the usual vibrator and any suitable source for energizing it, a battery 87 being shown. The secondary circuit 88 of each transformer has its terminals connected respectively with the grid and the negative side of the filament of a well known audion tube 89, so that when a potential is impressed upon either of the secondary circuits 88 the electronic flow through the tube will be either wholly stopped or sufficiently interrupted to arrest the circulation of current through a relay circuit 90 which includes a relay 91 and the filament and the plate of the tube. When no current is flowing through either one of the relays 91 its armature 92 is released and then current is flowing through fields and armature of the motor 59 in one direction. In Fig. 8 the armatures are both in closed position and both field circuits 93 of the motor are cut out, and the controlling contact finger 32 is in neutral position, but when the contact finger 32 is moved in either direction far enough to close the primary circuit of its associated transformer, the associated relay 91 will be de-energized and thus release its armature 92 to thereby close its associated field and armature circuits and cause the motor 59 to run. The direction of running of the motor will of course be determined by which one of the contact pins 48 is brought into action.

It will be understood that Fig. 8 shows the armatures of both relays 91 energized and that in that condition no current will be on the motor, and the same result would follow if both relays are de-energized. The direction in which this type of motor runs is determined by the relative polarity of the field and armature; reverse either and the motor will run in the opposite direction. In the drawing the field windings are terminated on 110 volt A. C. leads. The motor circuit can be closed only when relay armatures are in opposite positions. In Fig. 8 both relays are energized by the passage of plate current through the tubes 89. Maximum plate current is flowing and will continue as long as the grid has a negative polarity. As soon as a positive potential is impressed on the grid through the transformer secondary 88 the plate current is greatly reduced or ceases altogether, thereby allowing the corresponding relay armature to fall or spring back and thus cause the motor to run in the proper direction.

All the foregoing electrical devices except the motor 59 are desirably enclosed in a box or case 95 mounted on the frame of the machine.

The whole purpose of the electrical control shown in Fig. 8 is to avoid the necessity of having the contact finger 32 make forcible, actual contact with the contacts 48, as such forcible or pressure contacts would to an extent interfere with the delicacy of oscillations of the measuring-disc. Actual contact between 32 and 48 is avoided by the use of this spark coil which when these contacts approach each other will cause an arc or spark to form before the contacts come

together and thus avoid the necessity of physical pressure at the contacts. Ordinarily arcing at these contacts would be undesirable but in view of the need for delicately mounting the measuring-disc the arcing at least at the contacts is 5 highly desirable as it insures prompt and sure actuation of the motor even though the contacts be oxidized or dirty. By thus providing for arcing at the contacts I of course do away entirely with the necessity of making actual positive contacts but of course in the operation of the apparatus the movement of the finger 32 cannot in most instances be arrested quickly enough to prevent actual contact. My arrangement, however, does avoid all necessity of any considerable pressure of one contact against the other and that is the whole purpose of employing the spark coil. In the drawings the contact-pins 48 are illustrated as being set farther apart than is necessary for measuring the general run of liquids; in actual 20 practice I have found it to be desirable to set these contacts quite close together, even less than a quarter of an inch, and the closer together the contacts are set the more accurate will be the measurement of the viscosity. 25

The opposed contacts 48 may be rendered adjustable toward and from each other by any suitable means; I have shown set-screws 96 for this purpose. The adjusting of these contacts toward and from each other to vary the space in 30 which the contact 50 vibrates is important in that it enables me to adapt my device for nicety of measurement. The closer these contacts are set to each other, the nicer will be the degree of measurement of viscosity as is obvious. With regard to the two upstanding pins 45 it will be observed that these pins are located at opposite sides of the center of rotation of the shaft of the measuring-disc and that the connecting cord 37 is so arranged as to exert as nearly as possible 40 an equal pull on opposite sides of the pins; this is important in that it avoids any tendency to tilt the shaft of the disc and thus eliminates friction in the suspension bearing to as high a degree as possible. 45

I desire it to be understood that while the electric sensitive control system diagrammed in Fig. 8 is particularly desirous in connection with my viscosimeter apparatus, I believe that the principle therein is capable of use in other connections 50 and I therefore do not limit my claim solely for use in connection with viscosimeters.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means. Also, while it is designed 60 to use the various features and elements in the combinations and relations described, some of these may be altered and others omitted and some of the features of each modification may be embodied in the others without interfering 65 with the more general results outlined, and the invention extends to such use.

I claim:

1. In a viscosimeter, the combination of a tank, a driving-disc therein and means for rotating it at a constant speed, a companion measuring-disc, means for supporting said measuring disk face-to-face with respect to said driving-disc in such manner as to have a limited rotary movement in either direction, devices normally 75

- tending to rotate the measuring-disc in a direction opposite to the direction of movement of the driving-disc, whereby drag of the liquid between the discs tends to rotate the measuring-disc against its normal tendency, and power-driven reversible actuating mechanism for moving the measuring-disc toward and away from the driving disc, and means for putting said power-driven actuating mechanism into operation to move the measuring-disc away from the other disc when the drag overcomes its normal tendency to rotate and to move the measuring-disc toward the other disc when the drag is insufficient to overcome said normal tendency and viscosity-indicating-means actuated from said power-driven reversible actuating mechanism.
2. The structure recited in claim 1, said actuating mechanism embodying a reversible electric motor, circuits including a pair of opposed contacts, and a contact member attached to the measuring-disc whereby when the measuring-disc is rotated in one direction it will close one circuit and cause the motor to run in one direction, and when the measuring disc is rotated in the opposite direction it will close the other circuit and thus cause an opposite rotation of the motor.
3. The structure recited in claim 1, said actuating mechanism embodying a vertically movable rod on which is rotarily suspended the measuring-disc.
4. The structure recited in claim 1, said actuating mechanism embodying a reversible electric motor having two circuits, means actuated by the measuring-disc for closing one or the other of said circuits according to whether the measuring-disc is rotated by the drag of the

liquid or by its actuating devices, for the purpose set forth.

5. The structure recited in claim 1, a reversible electric motor being embodied in the actuating mechanism, means actuated from the rotary movements of the measuring disc for closing the circuits of this motor, to thus raise or lower the measuring-disc by power.

6. The structure recited in claim 1, the devices normally tending to rotate the measuring-disc embodying a pair of pins mounted at opposite sides of the center of rotation, and a tensioned spring arranged to pull in opposite directions on the opposite sides of said pins to thereby eliminate tendency to tilt the measuring disc axis, whereby friction is reduced to a minimum.

7. The structure recited in claim 1, the devices normally tending to rotate the measuring-disc embodying a pair of pins mounted at opposite sides of the center of rotation, and a tensioned spring arranged to pull in opposite directions on the opposite sides of said pins to thereby eliminate tendency to tilt the measuring disc axis, whereby friction is reduced to a minimum, and means for varying the tension of said spring.

8. The structure recited in claim 1, said reversible actuating mechanism embodying a reversible electric motor, said means for putting said actuating mechanism into operation embodying a movable contact finger, a pair of opposed contacts cooperating therewith, and electric means for producing an arc when said contact finger approaches either one of said contacts to thereby render actual physical contact unnecessary.

JOHN MONTGOMERY BELL.
